US00D989833S

(12) **United States Design Patent** (10) **Patent No.:** **US D989,833 S**
(45) **Date of Patent:** **** Jun. 20, 2023**

(54) **HOUSEHOLD ROBOT**

(71) Applicant: **SHENZHEN TCL NEW TECHNOLOGY CO., LTD.**, Shenzhen (CN)

(72) Inventors: **Tiago Abreu**, Shenzhen (CN); **Qingyu Chen**, Shenzhen (CN); **Weisi Zhan**, Shenzhen (CN); **Nairu Ge**, Shenzhen (CN)

(**) Term: **15 Years**

(21) Appl. No.: **35/514,865**

(22) Filed: **Jul. 15, 2022**

(80) **Hague Agreement Data**

Int. Filing Date: **Jul. 15, 2022**

Int. Reg. No.: **DM/222292**

Int. Reg. Date: **Jul. 15, 2022**

Int. Reg. Pub. Date: **Aug. 5, 2022**

(30) **Foreign Application Priority Data**

May 31, 2022 (CN) 202230329935.X

(51) **LOC (14) Cl.** **15-99**

(52) **U.S. Cl.**

USPC **D15/199**
